US00D759671S

(12) **United States Design Patent**
Zarick et al.

(10) **Patent No.:** **US D759,671 S**
(45) **Date of Patent:** **** Jun. 21, 2016**

(54) **DISPLAY SCREEN WITH GRAPHICAL USER INTERFACE**

(71) Applicant: **Microsoft Corporation**, Seattle, WA (US)

(72) Inventors: **Richard W. Zarick**, Seattle, WA (US); **Jeremy Monroe Bowen**, Renton, WA (US)

(73) Assignee: **Microsoft Corporation**, Redmond, WA (US)

(**) Term: **14 Years**

(21) Appl. No.: **29/503,815**

(22) Filed: **Sep. 30, 2014**

(51) LOC (10) Cl. **14-04**

(52) U.S. Cl.

USPC **D14/485**

(58) **Field of Classification Search**

USPC D14/485-495; D20/10, 11, 18, 22, 27, D20/28, 40; D18/12.3, 31, 41

CPC G06F 3/048-3/04897; G06F 2203/048-2203/04809; G06Q 30/06-30/0645

(57) **CLAIM**

The ornamental design for a display screen with graphical user interface, as shown and described.

DESCRIPTION

The FIGURE is a front view of a display screen with graphical user interface showing our new design.

The broken lines illustrate an electronic device with display screen and portions of a graphical user interface, and form no part of the claimed design.

1 Claim, 1 Drawing Sheet
